BALL ROLLING GAME

Herbert G. Breitenstein, Chicago, Ill., assignor to
Raymond T. Moloney, Chicago, Ill.

Original application April 18, 1934, Serial No.
721,119. Divided and this application March
24, 1937, Serial No. 132,789

3 Claims. (Cl. 273—118)

My invention relates to improvements in ball rolling or bagatelle games to make the playing thereof more interesting and fascinating, the present application being a divisional application 5 of my copending application Serial Number 721,119 filed April 18, 1934 for Game of skill.

These games comprise an inclined board or table provided with ball trapping holes, the balls being projectable to the upper end of the board 10 to gravitate thereafter down the board and into the holes. The present invention more particularly provides a particular type of ball closed trap door for certain or all of the holes so that when a hole once receives a ball, the door closes 15 and the hole cannot thereafter receive another ball, during the play of a given game cycle. Associated with the board and carried for sliding movement therebelow is a panel constructed in a manner when shifted to move a closed trap door to its hole opening or uncovering position.

The main object of the invention is to provide an improved trap door of the kind stated associated with novel, improved means to move a closed trap door to its hole uncovering position.

Other objects will become apparent to those skilled in this art as the disclosure is more fully made.

Briefly, such objects are attainable in a practicable form by mounting in a game board hole, 30 a hinged cover or door normally disposed in an upright hole uncovering position so that an angular leg extension of the door is disposed in the hole in a manner to receive a ball entering the hole. As the ball passes downwardly by gravity 35 through the hole, the leg is moved downwardly, with the ball causing the door to be moved hingedly from its normal position to a down position where it covers or closes the hole to prevent other balls thereafter from entering said 40 hole. Below the board is a shiftably carried panel having an opening therein into which the leg extension of the door extends when the door is in hole closing position. When the panel is shifted one end of the panel opening engages 45 the leg to move the door back to its raised hole uncovering position, there being operatively associated with the door, a spring to flip the door over its dead center position to insure full opening or closing of the door.

50 In the accompanying sheet of drawings:

Figure 1 is a general plan view of a ball rolling game;

Figure 2 is a longitudinal sectional view therethrough, taken along the line 2—2 of Figure 1, 55 looking in the direction of the arrows; and,

Figure 3 is an enlarged, detail, longitudinal sectional view through the trap door structure, taken along the line 3—3 of Figure 2, looking in the indicated direction.

As shown in Figure 1 the game device is housed 5 in a box having a front wall 10, two side walls, 11, and a rear wall, 12, the box being closed at its top by the usual glass cover 13. The walls carry an inclined game board 14 having an oval play field 15 at one side of which is a ball shooting passage 16. At the lower end, adjacent the front wall 10, is a shooter or projector 17 for shooting balls, in the usual way, one at a time, onto the upper end of the playing field to gravitate therewith toward the front wall end 15 thereof. The board field 15 may be provided with any number of holes 18 formed therethrough to receive balls rolling over the field. Spent balls missing these holes 18 are received by a spent ball pocket or opening 19 formed in 20 the lower end of the board.

As shown best in Figure 3, each hole 18 has a trap door 20 pivotally mounted therein as shown for hinging movement, said doors each having a substantially right angular leg extension 21 25 depending downwardly when the door is in hole closing or covering position. These doors are normally in hole opening position as shown in the dotted lines in Figure 3 so that when a ball enters the hole it engages the leg 21 to pull 30 the door to hole covering or closing position in an obvious manner. The lower edge of each hole 18 adjacent the door hinge carries a flat spring 22, which serves releasably to lock the door 20 in either its open or closed position, said 35 spring also acting to press the door in one direction or the other as it is moved over dead center.

Underneath the board 15, and in close proximity thereto is slidably carried on suitable supports 23, a thin, flat panel 24 which is parallel 40 to the board and in the conventional manner by means of a spring 25 is urged in a direction toward the front wall 10. This panel 24 can be slid by a coin released slide 26 mounted in the wall 10, the slide 26 adapted to abut a shoulder 45 27 formed on the panel 24. The panel 24 is formed with elongated cut out openings 28 respectively positioned below the ball receiving holes 18 so that trapped balls may pass through the panel in an obvious manner into the cabinet 50 and onto a usual ball routing panel, not shown, for return to the projector 17 in a manner well understood in this art. It will be noted the front edge of the panel 24 is positioned normally under the hole 19 to support balls entering same. 55

Also, it is to be noted that when a door 20 is in hole closing position the leg 21 depends into the adjacent opening 28 of the panel. (See Figure 3.)

5 In operation, a ball enters an uncovered hole 18, engages the door leg 21 and closes the hole by pulling down the door 20 about its hinge as the ball drops through the hole 18. The spring 21 serves to snap the door over its dead center position to insure positive closing thereof. The ball also drops through the opening 28 in the panel 10 and the leg 21 now hangs into said opening 28. No further balls can enter a closed hole 18. At the termination of play the coin slide 26 is 15 operated to push the panel 24 rearwardly away from the front wall 10, causing the front end of opening 28 to engage and move the leg 21 to raise the latter and hinge the door 20 upwardly until the spring 22 is operative to snap the door to its 20 full raised hole uncovering position.

From this disclosure it will now be seen that an improved ball trapping and control means therefore have been provided.

It is the intention to cover all changes and 25 modifications of the example of the invention herein shown and described, which do not depart from the spirit and scope of the invention as defined in the following claims.

What is claimed is:

30 1. A game board having a hole therethrough, a trap door for the hole closed by a ball dropping through the hole, said door having a depending portion, a thin, flat slideable panel carried immediately below and in close proximity to and parallel with the board and formed with an opening 35 into which the depending portion projects when the door is in hole closing position, and means to slide the panel to cause the end of the opening therein to engage the depending portion to raise 40 the door to hole opening position.

2. In a ball rolling game having a board over which a ball is rollable to and into a hole formed therethrough, a door movably positioned in said hole and normally disposed in hole opening position whereby a ball may enter the hole, said door having an angularly related extension disposed in the hole when the door is in hole opening position to be engaged by a ball entering the hole and passing through the board to move said door to hole closing position, the combination with said 10 extension of a thin flat panel slidably carried immediately under the board in close proximity to and parallel therewith and formed with an opening through which the ball may pass and into which the extension extends when the door is 15 moved by a ball to hole closing position, and means for sliding the panel to cause an edge of the opening to engage the extension and move the door to its hole opening position.

3. In a ball rolling game having a board over 20 which a ball is rollable to and into a hole formed therethrough, a door hingedly carried in said hole, said door adapted to be moved to hole opening position, said door having an angular extension positioned across the hole when the door is 25 in hole opening position to be engaged by a ball entering and passing through the hole to move the door to hole closing position, a spring located in the hole bearing yieldably against the door in a manner to snap the door over dead center 30 when it is moved in either direction, the combination with said door extension of a thin, flat panel slidably carried immediately under and in close proximity to and parallel with the board and formed with an opening into which the extension 35 depends when the door is in hole closing position, and means to move the panel whereby an end of the opening engages the extension and causes the door to move to hole opening position.
